(57) **CLAIM**

The ornamental design for a crawl space door and frame with interior flange, as shown and described.

DESCRIPTION

FIG. 1 is a front plan view of a crawl space door and frame with interior flange showing our new design;

FIG. 2 is a front plan view of a crawl space door and frame with interior flange shown separately for clarity of illustration;

FIG. 3 is a side elevation view of the frame shown in FIG. 2, it being understood the opposite side is a mirror image thereof;

FIG. 4 is a top elevation view of the frame shown in FIG. 2, it being understood the bottom is a mirror image thereof; FIG. 5 is an enlarged front plan detail view of the frame shown in FIG. 2;

FIG. 6 is a front and top perspective view of the door and flange shown in FIG. 1; and,

FIG. 7 is a front and top perspective view of the frame shown in FIG. 2.
